UNITED STATES PATENT OFFICE.

FRANÇOIS C. DULAC, JULES C. VAGNOT, AND HENRI GUÉTAT, OF GRENOBLE, FRANCE.

GARMENT-FASTENING.

No. 801,974.

Specification of Letters Patent.

Patented Oct. 17, 1905.

Application filed August 27, 1898. Serial No. 689,668.

To all whom it may concern:

Be it known that we, FRANÇOIS C. DULAC, JULES C. VAGNOT, and HENRI GUÉTAT, citizens of the Republic of France, residing at 5 Grenoble, France, have invented certain new and useful Improvements in Garment-Fastenings, of which the following is a description.

This invention relates to garment-fastenings, and has for its objects to provide a simple and efficient fastening for gloves, boots, shoes, and other articles, which fastening is so constructed as not to become readily disconnected accidentally; and the invention consists in the novel combination of parts, as 15 hereinafter set forth, illustrated in the drawings, and pointed out in the appended claim.

In the drawings, Figure 1 is a sectional view, on an enlarged scale, showing the fastening in its locked position. Fig. 2 is a sectional view of the upper part of the fastening. Fig. 3 is an under side view of Fig. 2. Figs. 4, 5, and 6 show by a sectional elevation, a plan, and a bottom view, respectively, the lower part d.

25 The upper portion or section or head of the fastening comprises a covering-plate e, a hollow shank e², and a bottom plate b', secured to the shank, said plate b' being provided with independent openings b³. The lower section of the fastening comprises a plate d³, having openings d⁴, and the locking members comprise a base c³, secured to the plate d³ and having integral spring-shanks c⁴, which terminate at their upper ends in enlargements c 30 c'. The shanks c⁴ are spring-shanks, and when the enlargements c c' are to be forced through the openings b³ in the plate b' a certain amount of force is necessary in order to permit

the enlargements to enter the openings b³, and 40 after said enlargements have passed through the openings the shanks spring together again. This spring action adds to the security of the fastening. In Fig. 1 the enlargements c c' are shown in position in the chamber formed 45 by the plate e, shank e², and plate b'. a a' represent the leather or other fabric to which the fastening is secured.

When it is desired to separate or disconnect the parts of the fastening, the latter are operated at right angles to the direction indicated by the arrows shown in Figs. 3 and 5.

What we claim is—

A fastener for use as described, comprising upper and lower sections, the upper section 55 comprising a covering-plate e, a hollow shank e², a bottom plate b', secured to the shank, said plate b' being provided with independent openings b³, the said top and bottom plates and shank forming between them a chamber 60 and said upper section being secured to material a, the lower section comprising a plate d³, having openings d⁴, the locking members with a base c³, secured to the plate d³, the base c³ having integral spring-shanks c⁴, which 65 terminate at their upper ends in enlargements c, c', adapted to be inserted through the openings in the bottom plate of the upper section, said lower section being secured to material a'.

In testimony whereof we have hereto set 70 our hands in the presence of the subscribing witnesses.
